UNITED STATES PATENT OFFICE

HUGH R. GRABLE, OF CANTON, OHIO

ELEVATOR DOOR

Application filed February 17, 1930. Serial No. 428,860.

The invention relates to elevator doors and more especially to a safety device particularly adapted for use in self-operated elevators such as are in general use in small apartment buildings and similar places.

It has been found by experience that children have been frequently killed or seriously injured by playing in or around self-operated elevators. Particularly in apartment houses it is customary for children to enter these elevators in their play and it often happens that a child is in the elevator car when a person on a higher or lower floor presses the button to bring the elevator up or down as the case may be.

When the car starts to move, the child, being frightened, will jump from the floor of the car to the door sill and attempt to open the door and escape but often is trapped and crushed by the moving car before being able to open the door.

The object of the present improvement is to provide a safety device which entirely covers the door sill and prevents the child from jumping from the moving car onto the sill; and which is so constructed that any attempt, by the child, to jump onto the sill will throw him backward into the car where he will remain unharmed.

A further object is to provide such a device adapted for use upon plural section sliding doors and so constructed as to accomplish its purpose without interfering with the normal operation of the doors.

The above and other objects may be accomplished by providing inclined baffle plates at the lower portions of the door sections, arranged to extend over and cover the door sill when the door is in closed position, one of said baffle plates being hinged and means being provided for swinging said baffle plate inward, upon its hinge joint, to permit it to clear the baffle plate upon the other door section, when the door is opened.

Other objects will be hereinafter pointed

out or will be obvious from the following detailed description of the invention and the illustration thereof in the accompanying drawings, in which

Figure 1 is an elevation of an elevator door provided with the improved safety device to which the invention pertains, taken from the inside of the elevator car and showing the door in closed position;

Fig. 2, a fragmentary elevation of the lower inside portions of the sliding door sections, showing the door in the open position;

Fig. 3, an edge view of the lower portion of the door section provided with the stationary baffle plate showing the mechanism for operating the hinged baffle plate upon the other door section;

Fig. 4, a similar view of both door sections showing the door in closed position;

Fig. 5, a view similar to Fig. 4, showing the doors in the opening position;

Fig. 6, an enlarged fragmentary elevation of the lower portions of the two door sections, showing the same in closed position, parts being broken away to illustrate the mechanism;

Fig. 7, a similar view showing the position of the mechanism as the door starts to open; and

Fig. 8, an enlarged detail perspective view of the cam which operates the hinged baffle plate.

Similar numerals refer to similar parts throughout the drawings.

The door to which the invention is adapted is of the sliding section type and may comprise the sections 10 and 11, both adapted to be slidably moved to the right, as viewed in Fig. 1, as by means of the operating bar 12, of usual construction, the section 11 moving substantially twice as fast as the section 10 when opening or closing.

The usual sill 13 is located at the elevator landing directly beneath the doors and the inner edge portion thereof extends into the

elevator shaft in usual manner, as shown at 14.

The usual grooves 15 may be formed in the top surface of the sill to receive the depending studs 16 at the lower ends of the doors in order to guide the doors as they slide to open or closed position, it being understood that the doors are suspended from hangers of any usual and well known construction.

10 A downwardly and inwardly inclined baffle plate 17 is located at the lower portion of the door section 11 having the flange 18 at its upper edge for connection to the inner face of the door section and the horizontal lower flange 19 for connection to the door section.

15 As best shown in Fig. 3, it will be seen that this baffle plate extends over the sill to substantially the inner edge thereof, preventing a person from standing upon the sill when the door is closed.

20 The door section 10 has an end plate 20 fixed to the edge portion thereof away from the section 11, as by the screws 21 and an angle brace 22 is fixed to this end plate and supports one end of the angle iron 23 which extends substantially across the width of the door section 10 spaced therefrom as best shown in Figs. 4 and 5.

25 An upturned flange 24 is fixed to the inner end portion of the angle iron 23 and slidably engages the angle iron 25 which may be welded or otherwise attached to the under side of the horizontal flange 19 of the baffle plate 17.

30 The baffle plate 26 is hinged at its lower edge as at 27 to the angle iron 23 and is inclined inward and upward at substantially the same angle as the baffle plate 17 upon the door section 11, the upper portion of the hinged baffle plate being inclined toward the door section 10 at a greater angle, as indicated at 28, and having the angular flange 29 at its upper edge adapted to rest against the rail 30 upon the door section 10, when the door is in the closed position and adapted to slidably engage the rail 31 upon the door section 11 as the door moves to the open position.

35 40 As best shown in Fig. 4, this hinged baffle plate normally extends over the portion of the sill directly adjacent to the door section 10 and is downwardly inclined so as to prevent a person from stepping upon this portion of the sill.

45 50 As shown in the drawings, the hinged baffle plate is notched as at 32 at its upper corner adjacent to the door section 11 for a purpose to be hereinafter described.

55 60 Means are provided to swing the hinged baffle plate 26 away from the door section 10, when the door starts to open, in order to permit the door section 11 and baffle plate 17 carried thereby to slidably move across the inner face of the door section 10.

This means is illustrated in the drawings as including a lever 33 fulcrumed intermediate its ends as at 34 upon a base plate 35 which is attached to the inner side of the door section 11, behind the baffle plate 17 carried thereby.

65 70 A cam lug 36 is fixed to the free end of the lever 33, the other end thereof being provided with an elongated slot 37 engaged by a pin 38 carried by the upper end of the operating lever 39 which is fulcrumed intermediate its ends as at 40, upon the plate 35 and provided at its lower end with the curved lug 41 adapted to normally protrude into the aperture 42 in the sill when the door sections are in closed position, the spring 43 being connected to the lower portion of the lever 39 and to a stud 44 upon the plate 35, for normally holding the parts in this position.

75 80 The free end portion of the lever 33 is adapted to slide between the plate 35 and the guide bracket 45 carried thereby. A curved cam plate 46 is fixed to the inner side of the hinged baffle plate, near the end thereof toward the door section 11 and adapted to be engaged by the cam lug 36 upon the lever 33.

85 90 In the operation of the device, as the door is opened by means of the operating bar 12, the door sections 10 and 11 will both be slidably moved toward the right, as viewed in Fig. 1, the section 11 moving at a greater speed than the section 10.

95 100 The adjacent end portion of the baffle plate 17 will ride into the notch 32 of the hinged baffle plate as the door section 11 starts to overlap the section 10.

105 110 The operating lever 39 will be swung into the position shown in Fig. 7 as the curved lug 41 thereon is withdrawn from the aperture 42 in the sill, the pin 38 thereon riding through the slot 37 of the lever 33 and rocking said lever upon its fulcrum, resting the cam lug 36 against the curved surface of the cam plate 46, as shown in Figs. 5 and 7, swinging the hinged baffle plate outward so as to clear the door section 11 and the fixed baffle plate 17 thereon.

115 120 Further movement of the door section 11 relative to the section 10 will move the cam lug 36 beyond the cam plate 46, permitting the hinged baffle plate to drop back toward the door section 11, the upper flange 29 thereof slidably riding upon the rail 31 on the door section 11.

125 130 As the door is moved back to closed position, the cam lug 36 will again engage the cam plate 46 and then ride off of the same, permitting the hinged baffle plate to drop back against the door section 10 while the levers 33 and 39 will assume the normal position shown in Fig. 6 as the door reaches the fully closed position.

135 140 From the above it will be obvious that the sill is completely covered when the door is in closed position, thus preventing anyone from

stepping from the floor of the elevator car onto the sill.

Should a child attempt to step upon the sill, the inclined baffle plates will cause him to slide backward into the elevator car without danger of serious injury such as might be caused if he remained upon the sill and was unable to get the door opened before the car ascended or descended.

10 I claim:

1. In an elevator shaft having a door opening, a sill at the bottom of the door opening, a door in said opening comprising relatively slidable door sections, inclined baffle plates at the lower portions of the door sections and extending across the sill when the door is closed, one of said baffle plates being hingedly connected to the corresponding door section and arranged to slide over the other door section when the door is opened, and means for swinging said hinged baffle plate away from the door when the door is opened.

2. In an elevator shaft having a door opening, a sill at the bottom of the door opening, a door in said opening comprising relatively slidable door sections, inclined baffle plates at the lower portions of the door sections and extending across the sill when the door is closed, one of said baffle plates being hingedly connected to the corresponding door section and arranged to slide over the other door section when the door is opened, and means upon the other door section for swinging said hinged baffle plate away from the door when the door is opened.

3. In an elevator shaft having a door opening, a sill at the bottom of the door opening, a door in said opening comprising relatively slidable door sections, inclined baffle plates at the lower portions of the door sections and extending across the sill when the door is closed, one of said baffle plates being hingedly connected to the corresponding door section and arranged to slide over the other door section when the door is opened, and a lever upon the other door section for swinging said hinged baffle plate away from the door when the door is opened.

4. In an elevator shaft having a door opening, a sill at the bottom of the door opening, a door in said opening comprising relatively slidable door sections, inclined baffle plates at the lower portions of the door sections and extending across the sill when the door is closed, one of said baffle plates being hingedly connected to the corresponding door section and arranged to slide over the other door section when the door is opened, and a cam upon the other door section for swinging said hinged baffle plate away from the door when the door is opened.

5. In an elevator shaft having a door opening, a sill at the bottom of the door opening, a door in said opening comprising relatively

tively slidable door sections, inclined baffle plates at the lower portions of the door sections and extending across the sill when the door is closed, one of said baffle plates being hingedly connected to the corresponding door section and arranged to slide over the other door section when the door is opened, and a cam lever upon the other door section for swinging said hinged baffle plate away from the door when the door is opened.

In testimony that I claim the above, I have hereunto subscribed my name.

HUGH R. GRABLE.
